(57) **CLAIM**

The ornamental design for a transmission jack, as shown and described.

DESCRIPTION

FIG. 1 is a left perspective view of the transmission jack according to the present design;

FIG. 2 is a left side view of the transmission jack as shown in FIG. 1;

FIG. 3 is a right side view of the transmission jack as shown in FIG. 1;

FIG. 4 is a front view of the transmission jack as shown in FIG. 1;

FIG. 5 is a rear view of the transmission jack as shown in FIG. 1;

FIG. 6 is a top view of the transmission jack as shown in FIG. 1; and,

FIG. 7 is a bottom view of the transmission jack as shown in FIG. 1.

The broken lines in the figures are for the purpose of illustrating portions of the transmission jack that form no part of the claimed design,
